UNITED STATES PATENT OFFICE.

ABRAM E. SMITH, OF BROOKLYN, NEW YORK.

RAILROAD TANK-CAR.

1,245,281.

Specification of Letters Patent. Patented Nov. 6, 1917.

Application filed December 6, 1915. Serial No. 65,210.

To all whom it may concern:

Be it known that I, ABRAM E. SMITH, a citizen of the United States, residing at New York city, borough of Brooklyn, in the county of Kings and State of New York, have invented certain new and useful Improvements in Railroad Tank-Cars, of which the following is a specification.

My invention relates more particularly to railroad tank cars, though it may be used in connection with other types of cars. I will describe a railroad tank car embodying my invention and then point out the novel features in claims.

In the accompanying drawings Figure 1 is a side elevation of a railroad tank car embodying my invention. Fig. 2 is an end elevation of the car shown in Fig. 1, but partly in double vertical section, the section being taken on the line 1—1 of Fig. 1 and looking in both directions of the arrows, the center anchor of Fig. 1 being shown to the left of the vertical center line on Fig. 2, and the end fastening of Fig. 1 being shown at the right of the center line on Fig. 2, the center anchor being shown as viewed from the right of Fig. 1 and the end fastening as viewed from the left of Fig. 1. Fig. 3 is a side elevation of a railroad tank car also embodying my invention and showing a fastening device at or near the end of a car body. Fig. 4 is an end elevation of the car shown in Fig. 3, but partly in double vertical section, the section to the left of the vertical line on Fig. 4 being taken on the line 4—4 and the section to the right of said vertical line being taken on the line 4^a—4^a of Fig. 3 and looking in the direction of the arrows. Fig. 5 is a detail perspective view of a form of fastening device embodying my invention which is used in Figs. 1 to 4, inclusive. Fig. 6 is a detail perspective view of a means which I preferably employ for preventing vertical and sidewise movements of the car body relatively to the underframe, but permitting of longitudinal expansion of the car body when the fastening device of Fig. 5 is used on one of the tank cars, as illustrated in Fig. 3.

Similar letters of reference designate corresponding parts in all of the figures.

1 designates an underframe which is suitably supported on wheels 2. The underframe 1, as here shown, comprises two longitudinal sills 3, 4, which are suitably joined together, as, for example, by top and bot-

tom plates 5, 6^a, which extend the entire length of the sills, thus maintaining a uniform strength of the underframe throughout the entire length thereof.

60

6 designates a car-body of any desired form. As here shown, the body 6 is in the form of a tank which may be of any suitable construction well known in the art. The tank may also be provided with heating apparatus and an inlet and outlet for its contents.

65

Referring now more particularly to Figs. 1 and 2, the body 6 is supported on the underframe 1, near the ends thereof, in saddles 7, and the body 6 is detachably secured to the saddles 7 by means of nuts and bolts 8 which pass through flanges 9 carried by the saddles 7 and flanges 10 of angle iron which are riveted to the body 6. The openings in the flanges 9 and 10, through which the bolts pass, are elongated so as to permit of longitudinal expansion of the body 6. The purpose of the above-described connection is also to prevent vertical and sidewise movement of the body relatively to the underframe. This form of connection is set forth in Patent No. 1,100,405, granted to me June 16, 1914. Other means for preventing relative vertical and sidewise movements between the tank and underframe may be provided, provided such means will permit of longitudinal expansion of the body 6.

70

75

80

85

In Fig. 1 the body 6 is connected with the underframe by the device or anchor 90 shown in detail in Fig. 5 at about the middle of the body 6. The device or anchor for making this connection comprises a part 11 connected to the body 6, as here shown by rivets 11^b, and a part 12 connected to the 95 underframe, as here shown by rivets 12^b, and bolts 13 for uniting the parts 11 and 12. The parts 11 and 12 may be castings of steel or other suitable metal. The part 11 is provided with a series of ribs or projections 11^a suitably spaced apart, which interengage with a series of ribs or projections 12^a provided on the part 12. The projections 11^a and 12^a are provided with openings 11^c and 12^c which register, when the 100 car is on the underframe, and through which the bolts 13 pass, each bolt being held in its openings by means of a nut 13^a. The bearing surface of the ribs or projections 11^a, 12^a, as well as their shearing value, is increased by extending them beyond the frame. The center of gravity of the car is also low-

105

110

ered by having the ribs extend beyond the underframe so that the bolts 13 may be inserted as low as possible relatively to the top of the underframe. The bolts 13 are used only to prevent vertical movement of the body 6 relatively to the underframe.

Referring now to Figs. 3, and 4, the fastening device or anchor of Fig. 5 is placed at one end of the body 6, as shown in Fig. 10 3, and the means shown in Fig. 6 is employed at the other end of the body. These means (Fig. 6) comprise a part 15 connected with the body 6, as here shown by rivets 15^b, a part 16 connected with the underframe, as 15 here shown by rivets 16^b, and one or more bolts 17, each provided with a nut 17^a, which extend through openings 15^c and 16^c which register when the car is upon the underframe. The parts 15 and 16 may be cast 20 ings of steel or any other suitable metal. The part 15 is provided with one or more ribs or projections 15^a, which interengage with ribs or flanges 16^a carried by the part 16. The openings 15^c are preferably elongated to permit of longitudinal expansion of 25 the body 6.

The two devices at the ends of the body in Fig. 3 also prevent vertical and lateral movement of the body relatively to the underframe.

Having thus described my invention, what I claim as new is:—

1. The combination in a railroad car, of a car-body, an underframe, and a fastening 35 between the underframe and body, said fastening comprising a part connected with the car-body and provided with one or more ribs or projections, a part carried by the underframe and having ribs which interengage with the said ribs or projections, and bolts which pass through registering openings in the said two parts.

2. The combination in a tank car, of a tank, an underframe, and a fastening 45 between the tank and underframe comprising a part carried by the tank having ribs or projections extending transversely of the tank, a part carried by the underframe and having ribs or projections extending transversely of the underframe over the top thereof, which ribs or projections interengage with the ribs or projections of the part carried by the tank, and bolts passing through the said ribs or projections.

3. The combination in a tank car, of a tank, an underframe, and a fastening between the tank and underframe comprising a part carried by the tank having ribs or projections extending transversely of the tank, a part carried by the underframe and having ribs or projections extending transversely of the underframe over the top thereof, which ribs or projections interengage with the ribs or projections of the part carried by the tank, and bolts passing through the said ribs or projections at the end portions of the ribs or projections.

4. The combination in a tank car, of a tank body, an underframe including a central longitudinal sill, and an anchor for securing the tank body to said sill, said anchor comprising two series of projections secured respectively to the sill on opposite sides thereof, and projecting laterally therefrom, said series extending longitudinally of the sill, and two series of projections secured to the tank on opposite sides of the sill and extending downwardly from the tank, each series of tank projections extending longitudinally of the sill and interengaging with the series of projections on the sill, and a fastening bolt securing each series of tank projections to the sill projections and extending longitudinally of the sill.

5. The combination in a tank car, of a tank body, an underframe including a central longitudinal sill, and a fastening between said tank body and the center sill comprising a part connected to the tank body, and a part connected to the underframe, the first-named part consisting of two series of projections each extending longitudinally of the tank body and located on opposite sides of the center sill, and the last-named part consisting of two series of projections each extending longitudinally of the center sill and interengaging with the projections on the tank body and a bolt extending longitudinally of the center sill and securing the projections on the center sill to the projections on the tank body.

In testimony whereof I have hereunto signed my name in the presence of two subscribing witnesses.

ABRAM E. SMITH.
